UNITED STATES PATENT OFFICE

2,381,106

HEATING FURNACE

Joe Cafagno, Marion, Ohio

Application December 27, 1944, Serial No. 570,037

5 Claims. (Cl. 263—6)

My invention relates to heating furnaces, and more particularly to a device for insuring an uninterrupted flow of material through furnaces used for heating steel rails, billets and similar materials preparatory to processing them in shears, rolls or other forming devices.

Furnaces of the above type have skids or rails extending for their full length along or near the floor of the heating chamber on which the rails or billets travel as they are introduced at the receiving end and caused to pass successively through the heating chamber to the discharge end. These rails or billets are often used and worn railroad rails which have been cut to length in relation to the width of the furnace available for the heating operation.

The rails or billets are placed on the skids at the receiving or charge end of the furnace and are introduced into the heating chamber by some device not directly in connection with the furnace, such as a hydraulic or pneumatic ram. The force is applied to each rail or group of rails placed on the skids at the charge end of the furnace, and such force is transmitted through the touching rails until a sufficient number have been introduced to force the first rail along the skids, through the heating chamber, to the discharge end of the furnace. The combined weight of the rails or billets under treatment, plus the retarding action of friction between the rails or billets and the furnace skids, requires a pressure of considerable force, generally of several thousand pounds, to deliver heated rails at the discharge end.

As the rails or billets used are, for the most part, worn railroad rails, and as the greatest amount of wear has produced a rounded corner on one or both top edges of the heads of the rails, a problem of maintaining proper relation of the rails in the furnace is created as follows:

(a) The general method of placing the rails on the skids is that they rest on one edge of the flange and one edge of the head with the head of one rail butting directly against the flange of the adjacent preceding rail.

(b) As pressure is applied at the charge end of the furnace and is transmitted through the touching rails, the head of each rail has a tendency to slide up on the bottom of the flange of the next adjacent preceding rail, thus producing a piling action.

(c) This piling action, if not prevented, results in a stoppage of furnace operation while the rails are restored to their proper positions for being forced through the furnace in an orderly manner.

(d) In addition to the piling action above described, there is a tendency of the rails, due to stress within the rails or billets being heated, to distort and warp along their longitudinal axes, thereby causing an action similar to that de-

scribed in paragraph (c) above and with the same results.

It is the purpose of this invention, therefore, to provide a device whereby the disadvantages mentioned in the above paragraphs are eliminated, so that the heating process will not be interrupted and will require a minimum of time and labor.

More specific objects and features of the invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is a side elevational view of a rail hold-down device constructed in accordance with the present invention and installed within a heating furnace, the furnace being illustrated diagrammatically and in longitudinal section.

Figure 2 is a transverse section taken on line 2—2 of Figure 1.

Figure 3 is a horizontal section taken on line 3—3 of Figure 1.

Figure 4 is an enlarged fragmentary view of a portion of the construction shown in Figure 1, to more clearly reveal details.

Referring in detail to the drawings, the present device includes a frame embodying a plurality of hold-down rails 10, preferably made from suitable lengths of standard railroad rail, and fastened to each other in the same horizontal plane and in spaced parallel relation by suitable cross bars 11 that are also preferably in the form of lengths of railroad rail. The hold-down rails 10 have their heads uppermost, while the cross bar rails 11 are inverted and butt-welded to the sides of rails 10 after having been cut as required for a snug fit.

Supporting rods 12 are welded at their lower ends to the heads of the hold-down rails 10 at or near their junctions with the cross bar rails 11, and they are of sufficient length to protrude through the top of the furnace F and to engage the spring assemblies A to be presently described.

Each spring assembly consists of a bottom bearing plate support 13, which can be I-beams as shown, or varied to suit the installation, and a bottom bearing plate 14 which rests on support 13 and in turn supports a compression spring 15 which is of sufficient strength to adequately support its portion of the weight of the entire assembly. The spring 15 surrounds the adjacent supporting rod 12, and the latter extends upwardly through the plate 14. Tension spring 16 is held in place by a top bearing plate 16 which is slidable on the supporting rod 12 and is, in turn,

secured by a nut 17 on the threaded upper end of the supporting rod 12.

A plurality of spaced cable supports 18, made of sections of steel pipe, are fixed to each rail 10, one end of each cable support resting on the flange of the associated hold-down rail 10 and securely welded in the position shown to the flange and head of this rail. The other end of the pipe section of each cable support 18 is closed by welding a circular plate 18a, of a diameter slightly greater than that of the pipe, over said other end as shown.

A cable guard bar 19, made from the flange of a standard railroad rail with a half-circular groove 19a milled along the top center to provide a runway or guide for a spacer block cable 20, is associated with each rail 10. The cable guide bars 19 are inverted and welded to the flanges of the hold-down rails 10 as shown.

A spacer block cable 20 is placed over the cable supports 18 of each rail 10 and in the groove of the associated cable guide bar 19 so as to form an endless loop from the front to the rear of the entire assembly as shown. To each cable 20 are fastened spacer blocks 21, with a spacing of suitable clearance between them. The cables 20 are tensioned so that they move freely over the cable supports 18 and along the cable guide bars 19, there being no motive power transmitted to the cables other than by the movement of rails through the furnace. The flexibility of the cables between spacer blocks 21 permits a change in the angular relation of the blocks.

The entire assembly supported by the rods 12 through the spring assemblies is suspended from the roof of the furnace at a height above the rail skids of the latter to permit the flanges of the hold-down rails 10 to touch the flanges of the rails being heated, as shown.

As rail sections are introduced into the furnace for treating, the top portions of their flanges will engage the spacer blocks 21, as shown, and move the spacer bar cables 20 in a direction toward the rear of the furnace, thus presenting additional spacer blocks 21 for the engagement of succeeding rail sections. As this movement continues, hold-down rails 10 restrict any vertical movement of the rails under treatment, while the spacer blocks 21 prohibit any tendency that the heads of the rails may have to slide up on the flanges of the preceding adjacent rails, as noted above.

It will be noted that the length of the hold-down rails is not defined, because at one point in the heating process a granular scale is produced on the rails under treatment, which prevents the objectionable sliding and stacking. The hold-down rails need not, therefore, be extended beyond this point, which can be determined by an inspection of the specific furnace in which the installation is to be made.

From the foregoing description, it is believed that the construction and operation, as well as the advantages of the present invention, will be readily understood and appreciated by those skilled in the art. It will be apparent that I have provided a simple and efficient device which will eliminate the objections noted above. Minor changes may be made in details of construction, illustrated and described, such as fairly fall within the spirit and scope of the invention as claimed.

What I claim is:

1. In combination with a heating furnace, a hold-down device comprising an elongated rigid frame embodying a plurality of spaced longitudinal hold-down rails, a longitudinal series of spaced

cable supports mounted upon corresponding sides of said hold-down rails, a cable passing around the cable supports of each hold-down rail, a plurality of equally spaced spacer blocks carried by and projecting vertically from each cable, and means for suspending said frame from the roof of the furnace so as to locate the hold-down rails at a predetermined distance above the bottom surface of the furnace along which the articles to be treated are moved.

2. In combination with a heating furnace, a hold-down device comprising an elongated rigid frame embodying a plurality of spaced longitudinal hold-down rails, a longitudinal series of spaced cable supports mounted upon corresponding sides of said hold-down rails, a cable passing around the cable supports of each hold-down rail, a plurality of equally spaced spacer blocks carried by and projecting vertically from each cable, and means for suspending said frame from the roof of the furnace so as to locate the hold-down rails at a predetermined distance above the bottom surface of the furnace along which the articles to be treated are moved, said cable supports comprising flanged cylindrical members having their unflanged ends resting on the flanges of the hold-down rails and secured thereto and to the heads of said hold-down rails.

3. In combination with a heating furnace, a hold-down device comprising an elongated rigid frame embodying a plurality of spaced longitudinal hold-down rails, a longitudinal series of spaced cable supports mounted upon corresponding sides of said hold-down rails, a cable passing around the cable supports of each hold-down rail, a plurality of equally spaced spacer blocks carried by and projecting vertically from each cable, and means for suspending said frame from the roof of the furnace so as to locate the hold-down rails at a predetermined distance above the bottom surface of the furnace along which the articles to be treated are moved, said cable guide bars secured to the flanges of the hold-down rails and to the under sides of said cable supports, said cable guide bars having grooves to accommodate the cables.

4. In combination with a heating furnace, a hold-down device comprising an elongated rigid frame embodying a plurality of spaced longitudinal hold-down rails, a longitudinal series of spaced cable supports mounted upon corresponding sides of said hold-down rails, a cable passing around the cable supports of each hold-down rail, a plurality of equally spaced spacer blocks carried by and projecting vertically from each cable, and means for suspending said frame from the roof of the furnace so as to locate the hold-down rails at a predetermined distance above the bottom surface of the furnace along which the articles to be treated are moved, the means for suspending the frame including vertical supporting rods fixed to and rising from the frame and slidably projecting through the roof of the furnace, and yieldable means associated with said supporting rods and urging the latter upwardly to yieldingly support the frame.

5. As a means for preventing piling of rails while the latter are moved through a heating furnace, an elongated frame having longitudinal hold-down rails engageable with the flanges of the rails being treated, endless cables having spacer blocks engageable with the flanges of the rails being treated, guides for said cables, and means for suspending the frame at the desired elevation within the furnace.

JOE CAFAGNO.
